UNITED STATES PATENT OFFICE.

LAURENCE J. BERKELEY, OF RACINE, WISCONSIN, ASSIGNOR TO THE P. & M. COMPANY, OF CHICAGO, ILLINOIS, A CORPORATION OF ILLINOIS.

RAIL-ANCHOR.

1,356,690.

Specification of Letters Patent. Patented Oct. 26, 1920.

Application filed September 5, 1919. Serial No. 321,881.

To all whom it may concern:

Be it known that I, LAURENCE J. BERKELEY, a citizen of the United States, residing at Racine, in the county of Racine and State 5 of Wisconsin, have invented certain new and useful Improvements in Rail-Anchors, of which the following is a specification.

My invention relates to rail anchors, and has for its object to provide a new and improved rail anchor which will readily yield to compensate for the expansion or contraction of the rail to which it is applied, which will grip the rail with a spring pressure so as to resist the tendency which the 15 vibration of the rail, or other causes, has to loosening its effective grip on the rail, and which will increase its grip on the rail during any longitudinal creeping of the rail.

20 My invention contemplates a device made up of a plurality of parts, certain parts of which are made of cast metal and certain other parts being made of spring metal, though it will be obvious from the following description that modifications in structure might be made without departing from my invention.

The various parts of my preferred form 30 of anchor are of such construction that they may be readily constructed, assembled and permanently secured together at a minimum cost of labor and material. When the parts are assembled they provide, in effect, a one-piece anchor which is less expensive to 35 manufacture than a similar device made entirely of spring metal, and at the same time possess the meritorious features of a device made entirely of spring metal.

The invention is illustrated in the accompanying drawings, wherein:

Figure 1 is a plan view of one form of the invention, illustrating the manner in which it is applied to the rail;

Fig. 2 is an end view in elevation of the 45 device shown in Fig. 1;

Fig. 3 is a front view in elevation of the device, showing the rail in cross-section;

Fig. 4 is a view in perspective of the rail anchor shown in the preceding figures;

50 Fig. 5 is a plan view of a modification, illustrating the manner in which this form of anchor is applied to the rail;

Fig. 6 is an end view of the same;

Fig. 7 is a front view in elevation of the

anchor shown in Figs. 5 and 6 with the rail 55 shown in section; and

Fig. 8 is a view in perspective of the device shown in Figs. 5, 6 and 7.

Like characters of reference designate like parts throughout the several figures of the 60 drawings.

Referring first to Figs. 1 to 4 inclusive of the drawings: 10 designates a railroad rail and 11 one of the cross-ties on which the rail is supported. The form of the invention shown in these figures consists, preferably, of a casting member 12 and a spring metal member 13 which together embrace the base flange of the rail. The casting member is formed with a depending flange 65 14 adapted to bear against one of the vertical faces of the tie 11, and is formed with an integral, relatively narrow, jaw 15 which fits over one edge of the base flange of the rail. The casting member, preferably projects beyond the jaw, as indicated at 16 (Fig. 4), and is formed at its outer end with a curved recess 17. The spring element 13 is preferably round in cross-section, and is formed at one end with a hook or jaw portion 18 which fits over the opposite edge 70 of the rail base. The other end of the spring is bent as indicated at 19 so as to fit the curved recess 17, and is rigidly secured in a bore 20 formed in the casting by any suitable means, such for example as by a pin 21, as shown in Fig. 2. It will be obvious that the spring element 13 if desired might be secured in the casting by supporting it 75 in the casting mold and pouring the molten metal around it, instead of securing it in the bore 20, as above described.

When the casting and spring elements 12, 13, are secured together, the bent portion 19 of the spring substantially fits the curved 80 seat provided by the recess 17 in the casting, and the jaw end 18 of the spring extends 85 at an angle with relation to the face 22 of the jaw 15.

When applying the anchor to the rail, 100 the jaw 15 of the casting 12 is applied over one edge of the base flange and the tie abutting portion is so positioned with relation to the tie 11 that the toe portion 23 thereof engages one of the vertical faces of the tie. 105 When the anchor is thus far applied, the spring element 13 assumes a diagonal position under the rail base, substantially as in-

dicated in dotted lines at "A", (Fig. 1). The jaw end 18 of the spring element may then be forced in a direction away from the tie to the position shown at "B" in Fig. 1, 5 in which position the hook portion thereof will clear the vertical edge of the rail. Upon releasing the spring element it will return to its normal operative position, as 10 shown at "C" in Fig. 1. When the anchor is 15 in its operative position, the spring element 13 takes a shackle hold on the rail, and exerts sufficient pressure against the edge of the rail base to resist the tendency of the vibration of the rail, or other causes, to 20 loosen the effective grip of the device on the rail. Any longitudinal movement of the rail toward the tie increases the pressure of the tie abutting portion 14 against the tie and causes the casting element 12 to rock 25 in the direction indicated by the arrow in Fig. 1. The tie abutting foot 14 is preferably formed with a curved surface 24 to facilitate this operation. The rocking action of the casting tends to shorten the distance 30 between the jaws 15, 18, so as to increase the grip of the device on the rail. Any longitudinal movement of the rail toward the tie has a tendency to move the jaw end 18 of the spring element 13 toward the tie, and 35 30 in this way increases the grip of the device on the rail irrespective of any rocking movement of the casting member 12. During the rocking movement of the casting it will be seen that there is a combination of both 35 of the above gripping actions.

In Figs. 5 to 8 inclusive of the drawings, I have shown a modified form of rail anchor which consists of a casting member 25 formed with a curved tie-abutting flange 26. 40 This casting is formed on its top face with two upstanding flanges 27, 28, which are spaced apart as shown at 29. The outer ends of the flanges are curved in opposite directions, as shown at 30. A preferably 45 flat spring yoke 31 having rail base engaging jaws 32, 33, at opposite ends is secured in the space 29 between said flanges 27, 28 by a rivet 34. The spring yoke is also formed with reverse curves 35, 35, adapted 50 to normally seat against the curved portions 30, 30 of the flanges, so that the opposite ends of the spring yoke assume the positions shown at D, D', before the jaws 32, 33 are 55 sprung into engagement with the edges of the rail base. The jaws 32, 33, may be applied over opposite edges of the base flange of the rail by springing the ends of the yoke 31 in opposite directions until the edges 36, 37 of the jaws 32, 33, respectively 60 clear the vertical edges of the rail. The jaws being released in this position will assume their operative positions E, E', by spring action. When the spring yoke is in 65 its operative position, the straight portion 38 of the yoke extends at an angle with re-

lation to the longitudinal center line of the rail base. Any longitudinal movement of the rail toward the tie tends to rock the casting member 25 in the direction indicated by the arrow in Fig. 5, so as to increase the 70 gripping action of the jaws 32, 33 on the rail base.

I have illustrated my invention in certain specific embodiments, though I do not wish to limit myself to the exact structures shown 75 and described except in so far as specific limitations may appear in the appended claims.

I claim:

1. A rail anchor comprising a jaw element 80 to engage one edge of the base flange of a railroad rail and formed with a tie abutting portion, and a spring member associated with said element adapted to engage the opposite edge of the rail; said 85 spring member being formed to extend diagonally across the rail base and adapted to be strained in its application to the rail and said jaw element being adapted to rock during a creeping pressure on the rail to 90 increase the grip of the spring member on the rail.

2. A rail anchor comprising a jaw element 95 to engage one edge of the base flange of a railroad rail and formed with a tie abutting portion, and a spring member associated with said element adapted to engage the opposite edge of the rail; said spring member being formed to extend diagonally across the rail base and adapted to be flexed 100 at a point adjacent said element in its application to the rail and said jaw element being adapted to rock during a creeping pressure on the rail to increase the grip of the spring member on the rail. 105

3. A rail anchor comprising a jaw element 110 to engage one edge of the base flange of a railroad rail and formed with a tie abutting portion, and a spring member rigidly secured at one end to said element 115 and adapted to engage the opposite edge of the rail; said spring member being formed to extend diagonally across the rail base and adapted to be flexed at a point adjacent said element in its application to the rail and 120 said jaw element being adapted to rock during a creeping pressure on the rail to increase the grip of the spring member on the rail.

4. A rail anchor comprising a jaw element 125 to engage one edge of the base flange of a rail and formed with a tie abutting portion, and a spring bar, round in cross section, rigidly secured at one end to said jaw element and formed at the other end with a 130 hook adapted to grip the opposite edge of the rail base with spring pressure; said jaw element being adapted to be rocked during the creeping action of the rail to increase the grip of the device on the rail. 130

5. A rail anchor comprising a tie abutting member having a jaw adapted to engage one edge of the base flange of a rail and a spring member engaging the opposite edge of the 5 rail and engaged with said tie abutting member at a point longitudinally remote from said jaw.

6. A rail anchor comprising a tie abutting member having a jaw adapted to engage one 10 edge of the base flange of a rail and a spring member engaging the opposite edge of the rail and secured to said tie abutting member in advance of said jaw.

7. A rail anchor comprising a jaw member 15 and a spring member secured thereto which together embrace the base flange of a rail; the spring member being formed to extend diagonally across the rail base and the jaw member being adapted to be rocked 20 during the creeping action of the rail whereby the grip of the anchor on the rail is increased.

8. A rail anchor comprising a jaw member having a jaw member for engaging with 25 one edge of the base flange of a rail and a spring element secured to said jaw member and formed with means for engaging the opposite edge of said rail base; said jaw member being formed with a tie abutting 30 portion positioned with relation to the jaw whereby the creeping action of the rail toward the tie rocks the said jaw toward the tie and increases the grip of the device on the rail.

35. 9. A rail anchor comprising a jaw member having a jaw for engaging with one edge of the base flange of a rail and a spring element secured to said jaw member extending diagonally across the rail base and formed 40 with means for engaging the opposite edge thereof; said jaw member being formed with a tie abutting portion positioned with relation to the jaw whereby the creeping action of the rail toward the tie rocks the said 45 jaw toward the tie and increases the grip of the device on the rail.

10. A rail anchor comprising rail base engaging jaw members for engaging opposite edges of the base flange of a rail and a

tie abutting element positioned intermediate 50 said jaws and adapted to be rocked during the creeping action of the rail to increase the grip of the device on the rail.

11. A rail anchor comprising rail base engaging jaw members for engaging opposite 55 edges of the base flange of a rail and a tie abutting element positioned intermediate said jaws and adapted to be rocked on a vertical axis during the creeping action of the rail to increase the grip of the device on 60 the rail.

12. A rail anchor comprising rail tie engaging jaw members for engaging opposite edges of the base flange of a rail and a curved tie abutting element positioned intermediate 65 said jaws at a point adjacent one of said jaws and adapted to be rocked on a vertical axis during the creeping action of the rail to increase the grip of the device on the rail.

70 13. A rail anchor comprising in combination a spring member bent intermediate its ends and adapted to extend diagonally across the rail base to engage the edge thereof, and a tie abutting element seated against 75 the bent portion of said spring and adapted to be rocked by the creeping pressure to increase the grip of the device on the rail.

14. A rail anchor comprising in combination, a casting and a spring member secured 80 together and adapted to engage the opposite edges of a rail base with spring pressure; said casting being formed with a curved tie abutting portion and adapted to be rocked on a vertical axis during the creeping action 85 of the rail to increase the grip of the device on the rail base.

15. A rail anchor comprising in combination, a casting formed with a rail base engaging jaw, a tie abutting portion to the 90 rear of said jaw and formed with a bore terminating in a curved recess at the forward end of the casting and a spring metal element bent to seat in said curved recess, having one end secured in said bore, and provided at the other end with a hook portion 95 adapted to engage one edge of the rail base.

LAURENCE J. BERKELEY.
